US00D729730S

(12) **United States Design Patent**
Gillespie-Brown et al.

(10) **Patent No.:** **US D729,730 S**
(b4) **Date of Patent:** **** May 19, 2015**

(54) **POWER CHARGING RING**

(71) Applicants: **Jon Simon Gillespie-Brown**, Portola Valley, CA (US); **Thomas Erik Meyerhoffer**, Montara, CA (US)

(72) Inventors: **Jon Simon Gillespie-Brown**, Portola Valley, CA (US); **Thomas Erik Meyerhoffer**, Montara, CA (US)

(**) Term: **14 Years**

(21) Appl. No.: **29/457,066**

(22) Filed: **Jun. 6, 2013**

(51) LOC (10) Cl. **13-02**

(52) U.S. Cl.

USPC **D13/110**

(57) **CLAIM**

The ornamental design for a power charging ring, as shown and described.

DESCRIPTION

FIG. 1 is a front perspective view of a power charging ring showing our new design;

FIG. 2 is a front view thereof;

FIG. 3 is a back view thereof;

FIG. 4 is a top view thereof; and,

FIG. 5 is a bottom view thereof.

The broken lines shown represent unclaimed subject matter and form no part of the claimed design.

1 Claim, 5 Drawing Sheets
